PROTECTIVE RELAY

William E. Glassburn, Bloomfield, N. J., assignor
to Westinghouse Electric Corporation, East
Pittsburgh, Pa., a corporation of Pennsylvania

Application February 16, 1950, Serial No. 144,401

12 Claims. (Cl. 175—294)

1

My invention relates to protective relays such as are used to detect faults in an alternating-current system, and it has particular relation to a reversible-torque wattmeter-type overcurrent element such as is used in a high-speed directional overcurrent relay.

My invention is an improvement over the high-speed directional overcurrent relay which is shown in Fig. 3 of the Hoard Patent 2,379,905, granted July 10, 1945, in which the contact-element of a directional relay is used to disconnect one of the two windings of a high-speed wattmeter-type overcurrent element, so as to prevent said overcurrent element from producing any torque when the directional-element contact is open.

It is the principal object of my present invention to produce an improved high-speed directional overcurrent relay in which the overcurrent element is so controlled by a directional element that the direction of the torque or operating-force which is produced in the overcurrent element actually reverses, dependent upon the position of the directional-element contact.

The system-conditions under which my new relay-control is needed, and the nature and structural design of my improved relay, will be hereinafter described and claimed, with reference to the accompanying drawing, wherein the single figure is a diagrammatic view of circuits and apparatus illustrative of a suitable form of embodiment of my invention.

In the drawing, I have illustrated my invention as being embodied in a phase-A relay which is used in the protection of a three-phase transmission or distribution line 1. The line 1 is connected to a station-bus 2 by means of a circuit-breaker 3 which is provided with an auxiliary breaker-contact 3a and a trip coil TC. Line-current for relaying purposes is derived by means of a bank of line-current transformers 4, and line-voltage for relaying purposes is derived by means of a bank of potential transformers 5.

My relaying apparatus, as illustrated, comprises a directional element D, which responds to the direction of the line-current I in phase-A of the line 1, and an overcurrent element HR which responds to a predetermined magnitude of the line-current I. Both of these relay-elements D and HR are of the product-responsive type, by which I mean the type of relay which develops a torque or operating-force which is proportional to the product of two single-phase fluxes, multiplied by a function of the phase-angle or time-phase between them. This prod-

2

uct-responsive effect can be produced, either in a differential type of relay in which either the operating force or the restraining force is responsive to the resultant of two out-of-phase currents or fluxes, as illustrated in the Goldsborough Patent 2,404,955, granted July 30, 1946, or it can be produced in a wattmetric type of relay in which the stator-member has two flux-producing windings for producing two interacting single-phase magnetic fluxes having poles which are displaced spatially relative to each other, and a rotor member which is so disposed as to produce a torque which is proportional to the product of these two single-phase fluxes multiplied by a function of the time-phase between them, an illustrative example of such wattmetric-type relay being shown in the previously mentioned Hoard patent.

In the drawing, the directional element D is illustrated as having a current-winding 11, a voltage-winding 12, and two sets of make-contacts 13 and 14. The current-winding 11 is shown as being energized by the line-current I, as derived by the line-current transformer 4. The voltage-coil 12 is illustrated as being energized from the phase AB voltage, as derived by the potential transformers 5, with a resistance R in series with said voltage-winding 12.

The overcurrent relay HR is illustrated as having two current-responsive windings 21 and 22, and a make-contact 15. Some dephasing means should be associated in shunt-circuit relation to one of the windings, such as 22, of the overcurrent element HR, so that the fluxes which are produced by the two windings 21 and 22 of this relay shall not both bear the same time-phase relation to the energizing-currents which are supplied to said windings, when said windings are connected together in series with each other. The dephasing means which I have illustrated for this purpose is a short-circuited lagging-coil 23. In a broader sense, however, such lagging-coil means should be construed as being representative of any means which causes the two fluxes of the overcurrent relay HR to be dephased with respect to each other when the two current-winding circuits are connected in series with each other, so that the fluxes are neither in exact phase with each other or in exact phase-position.

In the illustrated form of embodiment of my invention, the two current-coils 21 and 22 of overcurrent element HR have a common terminal 24. These two current-coils 21 and 22 are provided with separate energizing-circuits 31 and 32, respectively, branching back from said com-

mon terminal 24, the other terminals of these two separate energizing-circuits being indicated at 31' and 32', respectively.

I provide an auxiliary current-transformer 33, having a tapped-changing primary winding 33' which is energized by the line-current I in series with the current-winding 11 of the directional element D. The transformer 33 is shown as having a separate secondary winding 34, although an autotransformer could have been used, with the same winding serving as both the primary and the secondary windings. The secondary winding 34 has terminals 31' and 34', and these terminals 31' and 34' serve as the two terminals of a single-phase voltage-source which is used to energize the energizing-circuits 31 and 32 of the two current-windings 21 and 22 of the overcurrent element HR. The secondary winding 34 has an intermediate tap 32', so that this secondary winding 34 serves broadly, in effect, as an impedance-means having the two terminals 31' and 34', and an intermediate tap 32'. The supply-terminals 34' is connected to the directional-element contact 13, and thence to the common terminal 24 of the two current-coils 21 and 22 of the overcurrent element HR, while the other terminals 31' and 32' of the current-coils 21 and 22, respectively, are connected to the other source-terminal 31' of the secondary winding 34, and to the intermediate secondary tap 32', respectively.

The tripping-circuit is shown as being connected from a positive battery-terminal (+), through the make-contact 15 of the overcurrent element HR, and the make-contact 14 of the directional element D, and thence to the trip coil TC, the circuit being completed by the auxiliary breaker-contact 3a and the negative battery terminal (-).

The polarities of the connections of the overcurrent element HR are such that this element develops a contact-closing torque when the flux produced by the unshaded coil 21 leads the flux produced by the shaded coil 22 by a certain angle such as 45°. This condition is produced when both of these coils 21 and 22 are energized in the same polarity, which is the case when the directional-element contact 13 is closed. In such a case, the coil 21 is impressed with a voltage from 31' to 34', and while the coil 22 is impressed with a substantially in-phase, but smaller, voltage from 32' to 34'. When the directional-element contact 13 is open, however, the two coils 21 and 22 are connected in series with each other, across the voltage from 31' to 32', so that the polarity of the coil 22 is reversed. The impedances of the two coils 21 and 22 may conveniently be designed so that they have the same impedance-angles, although this design-condition is not necessary.

As a result of the above-described connections, my overcurrent element HR has a restraining or contact-opening torque, when the directional-element contact 13 is open, and said overcurrent element has an operating or contact-closing torque when the directional-element contact 13 is closed. The contact-opening torque of the overcurrent element is in addition to any relay-bias which may be provided, for biasing the relay toward its open or non-responsive condition, as indicated at 40.

My relay is designed so as to have its negative or contact-opening torque when the directional-element contact 13 is open, in order to avoid a possible erroneous relaying operation on the protected line 1. It will be understood that the directional element D is more sensitive than the

overcurrent element HR, so that the directional element D responds to the direction of the line-current I, or to the phase of this line-current with respect to the line-voltage in phase AB, without attempting to discriminate between heavy currents and light currents, or between fault-currents and load-currents. The directional element D thus responds to the direction of the load-currents which are flowing in the line 1 when there is no fault-condition. The overcurrent element HR, on the other hand, is designed to pick up, or respond, or close its contact 15, only when the magnitude of the line-current I is sufficient to indicate a fault-condition as distinguished from the maximum load-current which the line carries.

When the line-current I is flowing into the protected line-section 1, away from the station-bus 2, the directional element D responds, and closes its contacts 13 and 14. Under these conditions, that is, during normal load-conditions, when there is no fault on the protected line-section 1, but with the load-current I flowing away from the station-bus 2, as indicated by the current-arrow I, the directional-element contacts 13 and 14 will both be closed, and the overcurrent element HR will develop a torque in the current-closing direction, but this torque will not be sufficient to overcome the force of the biasing spring 40, so that the overcurrent-element contact 15 remains open. If, now, an internal fault occurs, that is, a fault having a current flowing in the tripping direction, the current I in the protected line-section reaches a magnitude sufficient to cause the overcurrent element HR to close its contact 15, thus instantly tripping the trip-coil TC, because the directional-element contact 14 is already closed, since the line-current immediately preceding the fault was in the tripping direction.

Now, still assuming that the load-current I is flowing in the tripping direction, that is, out into the protected line-section 1, let us assume that an external fault occurs, which may be on the station-bus 2, or somewhere on the system back of this station-bus 2, so that the fault-current now reverses and flows back towards the station-bus 2. When such a fault occurs, the overcurrent element HR will at first be in an energized condition in which it develops an operating torque, so that it will start to close its contact 15. The directional element D, at the same time, will start to open its contacts 13 and 14, which had been closed, because of the direction of flow which was assumed for the load-current immediately previous to the fault. A proper co-ordination of the contacts can easily be managed, by the proper setting of the contact-follow and travel, so that the directional element D will be able to get its closed contacts 13 and 14 open before the overcurrent element HR can travel far enough to close its contact 15, thus preventing tripping, which is the desired result when the fault-current is in the non-tripping direction.

Such an external fault, however, will have to be cleared by some other protective relaying devices (not shown) which are designed to respond to faults occurring within the place where the assumed fault is located, and when these other protective relaying devices respond, and cause a circuit-interrupting operation somewhere else in response to the fault, the fault might be cleared, while the overcurrent-element contact 15 is still closed, or while the overcurrent element HR is still drifting, by its own inertia, in the contact-closing direction. As soon as the ex-

ternal fault is cleared, the directional element D will reclose its contacts 13 and 14 as a result of the load-current which has been assumed to be flowing in the tripping direction. Hence, if the over-current contact 15 were permitted to close, as a result of this inertia-responsive drifting, the reclosure of the directional contact 14 would instantly cause an unwanted tripping operation, resulting in an opening of the circuit breaker 3 which supplies power to the sound line 1 from the station-bus 3.

In previous systems, such as that which is shown in Fig. 3 of the previously mentioned Hoard patent, where the overcurrent element was merely deenergized, not reversed in torque, in response to an opening of the directional contact 13, there was considerable danger that the overcurrent element would continue to drift into its closed-contact position, after the directional contact 13 had initially opened. In my system, however, the opening of the directional contact 13 does not merely deenergize the directional element HR, or kill its contact-closing torque, but it actually reverses the torque of this overcurrent element, so that this reversed torque will react against the inertia which tends to cause said element to continue to move in its contact-closing direction after the directional contact 13 has opened. The result of my reversed torque is thus a great reduction in the possibility of the incorrect tripping which would result if the overcurrent contact 15 should be closed at the instant when the external fault was cleared by other means (not shown), and when the directional contact 14 should reclose in response to a load-current flowing in the tripping direction.

If the load-current is in the non-tripping direction, that is, out of the protected line-section, and toward the station-bus 2, there will be a proper operation for all faults within the sensitivity of the elements, because the load-current causes the directional contacts 13 and 14 to be open. An internal fault will first cause the directional contacts 13 and 14 to close, after which the overcurrent element HR will develop a torque in the contact-closing position and will close its contact 15, thus producing a tripping operation. If the fault is in the non-tripping direction, the directional contacts 13 and 14 will remain open, the same way they had been in response to the load-current, and the torque of the overcurrent element HR will remain in the contact-opening direction so that the overcurrent contact 15 will not close.

While I have described my invention, and explained its method of design and operation, with reference to but a single form of embodiment, I wish it to be understood that the chosen embodiment is only illustrative, and that my invention is susceptible of various changes by way of the substitution of equivalent parts or the addition or omission of parts and refinements. I desire, therefore, that the appended claims shall be accorded the broadest construction consistent with their language.

I claim as my invention:

1. In combination: a single-phase product-responsive relaying element having contact-means, two flux-producing winding-means for producing two interacting single-phase magnetic fluxes which are so disposed as to produce a force which is proportional to the product of the two single-phase fluxes multiplied by a function of the time-phase between them, and an

energizing-circuit for each of said winding-means, the two energizing-circuits having one terminal in common; in combination with a single-phase voltage-source having two terminals, an impedance-means having two terminals and an intermediate tap, the two terminals of the impedance-means being connected to the two terminals of the voltage-source, means including a circuit-making and -breaking device for causing the common terminal of said two energizing-circuits to be either connected to one terminal of said impedance-means or disconnected from said impedance-means, and circuit-means for connecting the other terminals of the respective energizing-circuits to the other terminal and the intermediate tap, respectively, of said impedance-means.

2. A high-speed directional overcurrent relay adapted for use on an alternating-current system and characterized by having an overcurrent element as defined in claim 1, and a directional element for responding to the phase of a line-current with respect to a line-voltage, said directional element being operatively associated with the circuit-making and -breaking device referred to in said claim 1.

3. In combination: a single-phase product-responsive relaying element having contact-means, and two windings having one terminal in common; in combination with a tapped single-phase energizing-source having two terminals and an intermediate tap, means including a circuit-making and -breaking device for causing the common terminal of said two windings to be either connected to one terminal of said source or disconnected from said source, and circuit-means for connecting the other terminals of the respective windings to the other terminal and the intermediate tap, respectively, of said source.

4. A high-speed directional overcurrent relay adapted for use on an alternating-current system and characterized by having an overcurrent element as defined in claim 3, and a directional element for responding to the phase of a line-current with respect to a line-voltage, said directional element being operatively associated with the circuit-making and -breaking device referred to in said claim 3.

5. In combination: a single-phase product-responsive relaying element having contact-means, two flux-producing winding-means for producing two interacting single-phase magnetic fluxes which are so disposed as to produce a force which is proportional to the product of the two single-phase fluxes multiplied by a function of the time-phase between them, and an energizing-circuit for each of said winding-means, the two energizing-circuits having one terminal in common, said winding-means and their respective energizing-circuits being so related that the time-phase between the flux produced by one winding-means and the current carried by its energizing-circuit is different from the time-phase between the flux produced by the other winding-means and the current carried by its energizing-circuit; in combination with a single-phase voltage-source having two terminals, an impedance-means having two terminals and an intermediate tap, the two terminals of the impedance-means being connected to the two terminals of the voltage-source, means including a circuit-making and -breaking device for connecting the common terminal of said two energizing-circuits to one terminal of said impedance-means, and circuit-means for con-

necting the other terminals of the respective energizing-circuits to the other terminal and the intermediate tap, respectively, of said impedance-means.

6. A high-speed directional overcurrent relay adapted for use on an alternating-current system and characterized by having an overcurrent element as defined in claim 5, and a directional element for responding to the phase of a line-current with respect to a line-voltage, said directional element being operatively associated with the circuit-making and -breaking device referred to in said claim 5.

7. In combination: a single-phase product-responsive relaying element having contact-means, two windings having one terminal in common, and dephasing means associated with at least one of said windings; in combination with a tapped single-phase energizing-source having two terminals and an intermediate tap, means including a circuit-making and -breaking device for connecting the common terminal of said two windings to one terminal of said source, and circuit-means for connecting the other terminals of the respective windings to the other terminal and the intermediate tap, respectively, of said source.

8. A high-speed directional overcurrent relay adapted for use on an alternating-current system and characterized by having an overcurrent element as defined in claim 7, and a directional element for responding to the phase of a line-current with respect to a line-voltage, said directional element being operatively associated with the circuit-making and -breaking device referred to in said claim 7.

9. In combination: a single-phase product-responsive relaying element having contact-means, two windings having one terminal in common, and dephasing means associated in shunt-circuit relation to at least one of said windings; in combination with a tapped single-phase energizing-source having two terminals and an intermediate tap, means including a circuit-making and -breaking device for connecting the common terminal of said two windings to one terminal of said source, and circuit-means for connecting the other terminals of the respective windings to the other terminal and the intermediate tap, respectively, of said source.

10. A high-speed directional overcurrent relay adapted for use on an alternating-current system and characterized by having an overcurrent element as defined in claim 9, and a directional ele-

ment for responding to the phase of a line-current with respect to a line-voltage, said directional element being operatively associated with the circuit-making and -breaking device referred to in said claim 9.

11. A directional overcurrent relay adapted for use on an alternating-current system and characterized by having a directional element for responding to the phase of a line-current with respect to a line-voltage, an overcurrent element having two windings in such operative relation to each other that the overcurrent element develops a contact-opening force or a contact-closing force dependent upon the relative directions of the currents traversing said windings, and means under the control of said directional element for causing the two windings of said overcurrent element to be energized in one phase-relation when the directional element is in one position, and for causing said two windings of the overcurrent element to be energized in a substantially different phase-relation when said directional element is in its other position.

12. A directional overcurrent relay adapted for use on an alternating-current system and characterized by having a directional element for responding to the phase of a line-current with respect to a line-voltage, an overcurrent element having two windings in such operative relation to each other that the overcurrent element develops a contact-opening force or a contact-closing force dependent upon the relative directions of the currents traversing said windings, and means under the control of said directional element for causing the two windings of said overcurrent element to be energized in substantially the same polarity when the directional element is in one position, and for causing said two windings of the overcurrent element to be energized in the opposite polarity, one with respect to the other, when said directional element is in its other position.
